UNITED STATES PATENT OFFICE.

PAUL E. DOUGLASS, OF FLINT, MICHIGAN.

DESIGN FOR A PLATE.

48,930.

Specification for Design. Patented Apr. 25, 1916.

Application filed February 7, 1916. Serial No. 76,876. Term of patent 14 years.

To all whom it may concern:

Be it known that I, PAUL E. DOUGLASS, a citizen of the United States, residing at Flint, in the county of Genesee and State of Michigan, have invented a new, original, and ornamental Design for Plates, of which the following is a specification, reference being had to the accompanying drawing, forming a part thereof.

Figure 1 is a plan view of a plate; and

Fig. 2 is a sectional view taken through the plate showing my new design.

I claim:

The ornamental design for a plate, as shown.

PAUL E. DOUGLASS.

Witnesses:

ANDREW J. EICHORN,

KARL J. DOUGLASS.
